(57) **CLAIM**

The ornamental design for a lake rake, as shown and described.

DESCRIPTION

FIG. 1 is a top front left perspective view of a lake rake showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top rear right perspective view thereof;

FIG. 9 is a bottom rear left perspective view thereof;

FIG. 10 is a top rear right perspective view of the lake rake shown in an alternate state;

FIG. 11 is a top front left perspective view thereof;

FIG. 12 is a top front left perspective view of the lake rake shown in another alternate state;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof; and,

FIG. 18 is a bottom plan view thereof.

The broken line showing of a lake rake is for the purpose of illustrating portions of the article and forms no part of the claimed design.

1 Claim, 18 Drawing Sheets
